UNITED STATES PATENT OFFICE.

WALTER J. HARVEY, OF TORONTO, ONTARIO, CANADA.

DIURNAL REFLECTOR.

Application filed October 21, 1924. Serial No. 744,998.

The principal object of this invention is to devise a reflector which will follow the path of the sun's course and reflect its rays to a fixed point from all positions so as 5 to enable the utilizing of the concentrated rays.

The principal feature of the invention consists in supporting a reflector upon a vertical rotatable member and providing means 10 to swing the reflecting surface from a substantially vertical position to a substantially horizontal position and back again during the vertical rotation.

In the drawings, Figure 1 is an elevational and part vertical sectional view of the improved apparatus.

Figure 2 is a transverse vertical section of the column for supporting the reflector showing part of the mechanism arranged in 20 elevation.

Figure 3 is a plan view of the gear ring for operating the reflector.

The construction herein shown comprises a base 1 having a hollow column 2 rising 25 vertically centrally thereof.

A journal bearing 3 is arranged axially at the bottom of the hollow column and a journal 4 is supported at the top of the column in alignment with the bearing 3.

30 A shaft 5 is journalled in the bearings 3 and 4 and has secured to its upper end a standard 6 which rests upon a ball bearing 7 carried by the journal 4. The shaft and standard thus turn freely.

35 A bevelled gear 8 is secured to the lower end of the shaft 5 within the hollow base and is driven by a pinion 9 operated by a shaft 10 driven by any suitable form of controlled motive device. Such a device 40 operates to turn the shaft 5 one revolution in twenty four hours.

The upper end of the standard 6 is provided with a transverse shaft 11.

Upon the ends of this shaft are mounted 45 a pair of gear segments 12 and these are secured to the back of a reflector casing 13. The reflector is of a suitable construction to concentrate the sun's rays received thereon when said rays are directed on to the surface 50 at somewhat approaching a right angle and it is the purpose of this invention to maintain this reflecting surface in such a position throughout the day that the sun's rays will strike it at the desired angle at all times.

In order to accomplish this result, it is

necessary not only that the column should be rotated to swing the mirror to follow the sun around the perpendicular axis but because of the orbit of the sun in its passage 60 from horizon to horizon it is necessary to tilt the reflector, and to obtain this result a pair of spur pinions 14 are mounted on studs projecting from the rotatable standard 6 and these pinions mesh with the gear 65 segments 12.

A ring 15 is mounted upon the column 2 outside of the upper journal 4 and is provided with gear teeth 16 adapted to mesh with the gear pinions. These gear teeth extend substantially half way around the column so that as the column rotates upon its axis, the pinions on one side will travel for 70 a distance without meshing with the gear wheel ring 15.

In the operation of the device the shaft 10 is driven so as to rotate the vertical shaft 5 one revolution in twenty four hours and the pinions 14 and gear ring 15 are so arranged that at midnight one of the pinions will engage the gear teeth 16. As the column slowly turns, the teeth of the gear ring engaging the pinion carried by the column, causes the pinion to turn on its axis and this imparts a rotating movement to the gear segments 12 so that the reflector is gradually swung upon its transverse axis 80 toward a horizontal position.

In twelve hours the maximum movement of the reflector member has been reached. 90 During this period the pinion at the opposite side of the standard has been travelling free over the portion of the ring not provided with teeth but when the pinion which has been engaging these teeth disengages 95 therefrom, the other pinion comes into engagement and as it is arranged on the opposite side of the standard and connected with the gear segment on the opposite side, the movement of the pinion has the effect 100 of reversing the swinging movement of the reflecting member bringing it back toward the perpendicular.

It will thus be seen that the reflecting surface will follow the rising sun as its 105 elevation increases at mid-day when it reverses its movement and follows it toward its position at setting.

Thus, the device is utilized to its maximum efficiency in concentrating the sun's rays reflected therefrom over the maximum 110 period.

It will of course be understood that the location of the rising and setting of the sun varies as the seasons change and the position of the sun's rays differ according to its relation to the equator and the Tropics.

In in order to provide for this gradual change I have arranged the gear ring 15 in moveable relation to the standard and to this ring is connected a jointed lever 17 which is pivotally supported upon a stud 18 arranged intermediate of the height of the column 2. The lower end of the lever is connected to a pin 19 extending from a spur pinion 20 mounted on a fixed pivot in the column. The pinion 20 meshes with a pinion 21 carried upon a shaft 22 mounted in a bracket 23 and a ratchet wheel 24 is secured to the inner end of the shaft. This ratchet wheel is engaged by an arm 25 secured to the shaft 5 and at each revolution of the shaft 5, the arm engages a tooth on the ratchet wheel and turns it a short distance the size of the wheel and the number of the teeth being so proportioned that the lever 17 will be swung its maximum distance in either direction within the period of the change of the season occasioned by the different relation of the sun's rays to the Tropics.

30 What I claim as my invention is:—

1. A diurnal reflector, comprising a standard rotatable about a fixed vertical axis and adapted to be rotated continuously in one direction, a reflecting member carried by said rotatable standard and mounted for pivotal movement relative thereto, means for swinging said reflecting member on its pivot, and means actuated by said rotating standard for controlling said swinging means.

40 2. A diurnal reflector, comprising a standard rotatable about a fixed vertical axis and adapted to be rotated continuously in one direction, a transverse pivot carried by said standard, a reflector member mounted on said pivot, toothed gear segments secured to said reflecting member concentric with said transverse pivot, gear pinions mounted on said standard and meshing with said gear segments, means disposed in the path of travel of said pinions and adapted to engage the same to effect their rotation, and means actuated by said rotating standard operatively connected with said latter means for controlling the relation of same to said gear pinions.

50 3. A diurnal reflector, comprising a rigid column, a standard mounted on said column and rotatable in one direction about a vertical axis, means for rotating said standard, a gear ring on said column, means co-operating with said rotating standard for imparting a rotative movement to said gear ring in either direction, gear pinions mounted

on said standard and adapted to mesh with the teeth of said gear ring, a horizontal shaft mounted on said standard, gear segments secured to said horizontal shaft and meshing with said pinions, and a reflecting member secured to said shaft.

4. A diurnal reflector, comprising a rigid 70 tubular column having axially arranged bearings at its base and upper end, a shaft journaled in said bearings, a standard secured to the upper end of said shaft and rotatively mounted on the upper bearing, a 75 reflecting member pivoted to swing transversely on said standard, gear segments secured to said reflector member, gear pinions carried by the standard and meshing with said segments, a gear ring rotatably mounted on said column and adapted to mesh with said pinions, and means co-operating with the rotation of the vertical shaft for shifting the position of said gear ring.

5. A diurnal reflector, comprising a rigid 85 tubular column having axially arranged bearings at its base and upper end, a shaft journaled in said bearings, a standard secured to the upper end of said shaft and rotatably mounted on the upper bearing, a reflecting member pivoted to swing transversely on said standard, gear segments secured to said reflector member, gear pinions carried by the standard and meshing with said segments, a gear ring rotatably mounted on said column and adapted to mesh with said pinions, a lever pivotally mounted on said column and connected at its upper end with said gear ring, a crank member 90 operatively connected with the lower end of said lever, and means for rotating said crank member operated by the rotation of the vertical shaft.

6. A diurnal reflector, comprising a rigid 105 tubular column having axially arranged bearings at its base and upper end, a shaft journaled in said bearings, a standard secured to the upper end of said shaft and rotatably mounted on the upper bearing, a reflecting member pivoted to swing transversely on said standard, gear segments secured to said reflector member, gear pinions carried by the standard and meshing with said segments, a gear ring rotatably mounted on said column and adapted to 110 mesh with said pinions, a lever pivotally mounted in said column and connected at its upper end with said gear ring, a crank member operatively connected with the lower end of said lever, a gear operating said 115 crank member, a ratchet member connected with said gear, and a member carried by said shaft adapted to engage said ratchet member to effect the operation of said crank.
